UNITED STATES PATENT OFFICE.

LOWELL F. LINDLEY, OF CHICAGO, ILLINOIS.

SANITARY FLOORING.

1,319,879.

Specification of Letters Patent.

Patented Oct. 28, 1919.

Application filed March 29, 1919. Serial No. 286,001.

To all whom it may concern:

Be it known that I, LOWELL F. LINDLEY, a citizen of the United States of America, and resident of Chicago, county of Cook, and 5 State of Illinois, have invented certain new and useful Improvements in Sanitary Flooring, of which the following is a specification, and which are illustrated in the accompanying drawings, forming a part thereof.

10 The invention relates to a floor that is especially suitable for use in hospitals, a floor that shall be waterproof, sound proof, sanitary, durable, resilient and pliable. An object of the invention is to provide a floor 15 that will not crack even though the base upon which it is laid shall develop cracks. A further object is to provide a floor that will not only be sound proof as regards transmission of sounds to rooms lying below but shall give out practically no sound of foot falls into the room in which it is used. A further object is the provision of 20 a flooring that may be quickly and cheaply placed into position and may be put into use almost immediately when laid. A further object is the provision of a floor that shall be non-slippery. Further objects of 25 the invention will appear from the following description when read in connection 30 with the accompanying drawings, in which—

Figure 1 is a perspective view of a floor, different portions thereof being shown in different stages of construction; and 35 Fig. 2 is a cross section of a completed floor taken on the line 2—2 of Fig. 1.

Reference character 10 shows the base to which my improved floor is preferably applied, shown for purposes of illustration as 40 a concrete floor. It is to be understood that any other form of existing floor may properly be used but my invention has especial value in connection with concrete base since its resiliency overcomes the objection- 45 able harshness and unyielding nature of this type of floor. At 11 is shown a layer of cement. For purposes of illustration a pure asphalt is disclosed. This asphalt must be applied in a fluid condition and may be rendered fluid by use of any ordinary well known “cut back” or by heating the same.

In its cold or hardened condition this asphalt is preferably hard enough not to be affected by use of the floor but not sufficiently hard to be brittle. Upon the layer of 55 asphalt 11 a layer of fibrous material, shown as dry felt, 12, is applied. This layer of fibrous material is applied for the purpose of sound deadening and for the purpose of rendering the floor cover resilient under 60 foot. It is this layer particularly which takes away the objectionable resistance or harshness of a concrete floor as above referred to. A second layer of cement, shown as asphalt, is designated 13 on the drawing. 65 It is important that this layer of cement should be a waterproof cement and probably nothing better than an asphalt can be found for the purpose. This cement adheres firmly to the fibrous material especially well when 70 dry felt is used, as illustrated, and upon this layer the surfacing of the floor, shown as rubber, at 14, on the drawing, is applied. This surface layer must be applied while the cement is still sufficiently fresh to be 75 sticky. As shown at 15, 16, the joints of the surfacing material and the fibrous material are laid so as to “break” with each other. That is, one shall not fall in a vertical line with the other. 80

The surfacing layer 14 is preferably pure gum rubber without fabric of any kind, and due to the use of such a material my floor will have very long life in use. Moreover, this material is completely waterproof, may 85 be cleaned readily, is non-slippery, and in combination with the fibrous material shown, particularly when dry felt is used, will produce a floor of great resiliency and very pleasant and easy to walk upon. The prop- 90 erties presented by my floor have peculiar value for use in hospitals but are important wherever much walking about is to occur, as in kitchens or in public buildings.

I claim as my invention:

1. In a floor the combination of an unyielding base, a layer of cement on said base, a layer of dry felt lying upon and adhering to said cement a second layer of cement on said felt and a surface of sheet rubber 100 upon the last named layer of cement.

2. In a floor, an unyielding concrete base,

a layer of dry felt secured to said base by means of bituminous cement and a surface layer of sheet rubber secured to said felt by means of bituminous cement.

5 3. In a floor, a concrete base, a layer of bituminous cement upon said base, a layer comprising strips of dry felt placed edge to

edge lying upon and adhering to said cement, a layer of bituminous cement superimposed upon said felt and a surface layer ¹⁰ comprising strips of gum rubber lying edge to edge upon and adhering to said second named layer of cement.

LOWELL F. LINDLEY.
